SHEET METAL ROOF

Filed April 17, 1922

UNITED STATES PATENT OFFICE.

ROSS A. WORKMAN, OF TULSA, OKLAHOMA.

SHEET-METAL ROOF.

Application filed April 17, 1922. Serial No. 553,456.

To all whom it may concern:

Be it known that I, Ross A. WORKMAN, a citizen of the United States, residing at Tulsa, in the county of Tulsa and State of Oklahoma, have invented certain new and useful Improvements in Sheet-Metal Roofs; and I do hereby declare the following to be a full, clear, and exact description of the invention, such as will enable others skilled in the art to which it appertains to make and use the same.

The present invention relates to sheet metal roofs, and aims to provide such a roof wherein the seams between the adjacent longitudinal edges of the sheets will be capable of withstanding the tendency for the seams being torn open owing to the expansion and contraction of the roof.

In using conical sheet metal roofs or covers on large oil tanks, it has been found that on account of the large area to be covered, difficulty arises in taking care of the expansion and contraction, and not infrequently the seams between the sheets are torn open, leaving cracks or crevices. The demand is for a water and gas tight roof, which can be cheaply and conveniently applied, using regular straight stock sheets, the seams of which can be soldered to render the roof water and gas tight. When the roof expands, the sheets expand transversely, and in contracting, a great strain is placed on the seams between the sheets for drawing or pulling the sheets back into place, causing the seams to be weakened and opened, resulting in annoyance and necessary repairs.

It is an object of this invention to provide such a roof having seams which will be capable of withstanding the strains that tend to tear the seams open during the contraction of the sheets.

Another object is the provision of means combined with such a roof for relieving the seams of the greater portion or practically all of the tensile strains resulting from the contraction of the roof.

A still further object is the provision of expansion and contraction strips assembled with the roof and connected to the seams, to take care of the contraction of the sheets transversely and the pulling or drawing of the sheets without weakening or injuring the seams.

It is also an object of the invention to provide such improvements which do not in-

volve prohibitive trouble or expense, the construction being comparatively simple and cheap, as well as being easily applied.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:—

Fig. 1 is a plan view of a roof embodying the improvements, portions being broken away.

Fig. 2 is a vertical section on the line 2—2 of Fig. 1.

Fig. 3 is an enlarged vertical section showing two of the standing seams.

Fig. 4 is a perspective view of a portion of one of the expansion and contraction strips showing two of the seam anchors.

Fig. 5 is a longitudinal section of one seam, taken on the line 5—5 of Fig. 3.

The roof, as shown, is of conical form to be used on an oil tank, although the construction can be used in sheet metal roofs of different shapes with equal propriety when the sheets are subjected to transverse expansion and contraction.

The sheets 7 are laid in parallel rows, as usual, edge to edge, and the adjacent ends of the sheets of each row are overlapped and riveted or otherwise secured together to provide the lap seams 8. These seams are sufficiently strong to withstand longitudinal expansion and contraction of the sheets, without weakening or breaking, and said seams are also preferably soldered to prevent leakage.

The sheets 7 are joined at their adjacent longitudinal edges by standing seams 9. Each sheet 7 is provided at its opposite longitudinal edges with the upstanding seam portions 10 and 11, and the portions 10 and 11 of the adjacent sheets are secured together at intervals along the length thereof, by means of rivets 16, or the like, engaged through said portions and clamping them tightly together. Such rivets are spaced apart at suitable distances. Each portion 10 is formed with an upper flange 12 projecting away from the portion 11 of the corresponding seam, and the portion 11 has a

flange 13 projecting laterally in the same direction to overlap the flange 12. The flange 12 is wider than the flange 13 and is bent back upwardly to extend around the edge 14 of the flange 13 and overlap and bear on said flange 13. In this manner, the edge portion 14 of the flange 12 is clamped around the edge portion of the flange 13, and the flanges are soldered together, as at 15. A broad upwardly facing surface is thus provided to receive the solder, in order that the seam can be sealed to good advantage. The solder is also located as far as possible from the base of the seam where the greatest strain or separation occurs, in order that the solder will not be broken by any slight separation of the edges of the sheets.

In order to drag the sheets back into place during the contraction thereof transversely, 20 expansion and contraction strips 17 are laid on the sheathing 18 of the roof under the sheets 7 and extend transversely of said sheets. Wherever each strip passes under one of the standing or longitudinal seams, 25 an upstanding anchor piece or cleat 19 is secured on the strip, such anchor or cleat having a foot or base flange 20 riveted or otherwise secured on the strip transversely across the strip, and said anchor or cleat 30 having an angularly extending flange 21 at its upper end. These anchors or cleats are disposed between the portions 10 and 11 of the standing means, and each of said cleats 19 is engaged by at least one of the 35 rivets 16, thereby clamping the cleats in the standing seams, with the flanges 21 located between the flanges 12 and 13. In this manner, the cleats or pieces 19 are securely embedded within the standing 40 seams and being secured on the strips 17 will anchor the seams 9 to the strips 17, whereby, when the sheets 7 expand and contract transversely, the strips 17 expand and contract longitudinally of themselves, 45 and the roof will expand and contract with said strips. Furthermore, when the sheets 7 contract transversely, the strips 17 contract longitudinally, and the anchors or cleats 19 being secured in the standing 50 seams, will result in the sheets being dragged back into place with the strips 17. Each strip 17 in contracting will carry the cleats 19 with it, and such cleats will move the standing seams with them, so that the 55 sheets 7 are dragged transversely of themselves without imposing any appreciably strain on the seams 9. There is therefore a minimum possibility of the seams 9 being injured or torn open. When the strips 17 60 are in inclined positions, the feet 20 of the cleats 19 project toward the upper ends of the strips 17, whereby, during the contraction of the strips 17, a pull is exerted on the feet 20 instead of a compression force 65 which would be the case if the feet pro-

jected toward the lower ends of the strips. Thus, although the sheets 7 are pushed transversely down the grade or slope of the roof during the expansion thereof, such sheets are dragged back up the incline by 70 the strips 17, without throwing the entire strain on the standing seams as frequently, with the ordinary standing seams, results in the rivets pulling out or the solder breaking. With the present arrangement, there is 75 but a minimum strain applied to the standing seams, eliminating such strains on the seams as would be apt to injure or open same. The solder is also located as far as possible from the bases of the standing 80 seams, to be removed as much as possible from the point where the expansion and contraction occurs. The cross seams 8 are sufficiently strong to take care of the expansion and contraction without aid. 85

Having thus described the invention, what is claimed as new is:—

1. A sheet metal roof comprising sheets connected by seams, and expansion and contraction strips extending transversely under the seams, the sheets being anchored to said strips. 90

2. A sheet metal roof comprising sheets connected by seams, and expansion and contraction strips under the sheets extending 95 transversely below the seams, said seams being anchored to said strips.

3. A sheet metal roof comprising sheets connected by seams, expansion and contraction strips extending under the sheets transversely below the seams, and anchors secured to the strips and within said seams. 100

4. A sheet metal roof comprising sheets connected by standing seams, expansion and contraction strips below the sheets extending 105 transversely under said seams, and upstanding cleats secured to the strips and secured within said seams.

5. A sheet metal roof comprising sheets having upstanding portions along their 110 edges and securing elements engaged through said portions to fasten them together, expansion and contraction strips under said sheets extending transversely thereof, and upstanding cleats secured to 115 the strips and secured between said upstanding portions.

6. A sheet metal roof comprising sheets having upstanding portions along their 120 edges secured together, said portions having overlapping flanges extending laterally, one flange of each pair being bent back around the edge of the companion flange, expansion and contraction strips extending 125 transversely under the sheets, and upstanding anchor cleats having feet secured on said strips, said cleats being disposed between said portions and having upper flanges between the aforesaid flanges.

7. A sheet metal roof comprising sheets 130

connected by seams, and expansion and contraction means extending transversely of the sheets and seams and connected to said sheets for drawing or dragging them back into place during contraction of the roof.

In testimony whereof I have signed my

name to this specification in the presence of two subscribing witnesses.
